UNITED STATES PATENT OFFICE

2,493,469

RAILWAY COUPLER OPERATING DEVICE

William J. Tangerman, Hammond, Ind., assignor
to Standard Railway Equipment Manufacturing Company, Chicago, Ill., a corporation of
Delaware

Application May 15, 1946, Serial No. 669,880

9 Claims. (Cl. 213—170)

1

This invention relates to railway car coupler operating mechanisms, operable from the side of the car, and the principal object of the invention is to provide an operating rod having a handle at its outer end, said outer end being substantially non-rotatably supported by a bracket on the end of a car when said handle is in substantially vertical position, and having means at its inner end for attachment to the lock lifter of a car coupler so that upon rotation of said rod said lock lifter is swung to raise the coupler lock and thereby operate the coupler.

Another object of the invention is to so form the handle end of the rod relative to the supporting bracket so that, when in substantially vertical position swinging of the handle, due to service movements of the car, sufficiently to rotate the rod and thereby operate the coupler is practically eliminated, but when the handle is operated in the usual way by a trainman the structural relationship of the rod and bracket is such as to offer practically no resistance to said usual operation of the device by a trainman.

Another object of the invention is to form the rod and bracket so that when the handle is released by a trainman after operating the coupler the handle will return by gravity to substantially vertical non-rotatably supported position.

The desirability of substantially non-rotatably supporting a coupler operating rod when the handle thereof is in substantially vertical position has been recognized in the prior art, but in those instances of which applicant is aware, it is necessary for the handle to be operated in a manner peculiar to the specific operating device with which used, whereas with applicant's device, insofar as the trainman is concerned, the handle is swung manually in exactly the same manner as are the handles of the most commonly used coupler operating devices.

In the drawings:

Fig. 1 shows a typical application of my invention to a railway car.

Figs. 2, 3, 4 and 5 show the handle of the operating rod illustrated in Fig. 1 in the several operative positions hereinafter described.

Figs. 6, 7, 8 and 9 show a modified operating rod handle in several operative positions herein-after described.

Fig. 10 is a detail of the operating rod supporting bracket.

Figs. 4 and 8 also show a vertical section through member 9 showing the latter's connection to the car part 1.

In the drawings, Figs. 1, 2, 3, 4 and 5 show a

2

modification wherein the coupler operating rod 2 is operatively attached to the lock lifter 3 of the coupler 4 so that upon rotation of the rod the lock lifter operates the lock of the coupler.

5 The handle 6 is provided at the outer end of the operating rod; that is, adjacent the side 7 of the car, which handle is provided with a hook portion 8 engageable with the member 9 fixed to the car to substantially prevent accidental rotation of the rod due to service movements of the car when so engaged. (See Fig. 2.) The hook portion 8 is provided with an inclined surface 11 arranged so that swinging movement of the handle 6 by an operator slightly raises the operating rod and disengages the hook portion 8 from the member 9, (see Fig. 3), thus allowing the handle to be swung to rotate the operating rod to operate the coupler. (See Fig. 4.)

10 The outer part of the operating rod 2 is preferably supported by the hook portion 8 resting upon said member 9 when handle 6 is in substantially vertical position but I also provide a bracket 13 which is mounted upon the car, which bracket retains a journal portion of the operating rod adjacent the handle in a predetermined position so that the rod is actually rotatably guided by said bracket 13 because when the operating rod is raised by the elevation of the hook portion 8 the operating rod 2 actually engages and is supported 15 by the bracket 13 during the swinging movement of the handle. (See Fig. 4.)

20 The operating handle 6 is also provided with another inclined surface 14 adapted to engage said member 9 upon return of the handle to substantially vertical position and so as to raise said handle and rod and guide said hook portion 8 into engagement with the member 9. (See Fig. 5.)

25 In the modification shown in Figs. 6, 7, 8 and 9 the operating rod handle 20 is provided with a member or protuberance 21, which member is formed with an upwardly inclined under surface 22 which functions the same as the inclined surface 11 heretofore described and another inclined under surface 23 which functions the same as the inclined surface 14 heretofore described in the modifications shown in Figs. 1 to 5 inclusive. In 30 this group of drawings Fig. 6 shows the operating rod with member 21 resting upon the member 9; Fig. 7 shows the operating rod handle having been raised by the inclined surface 22; Fig. 8 shows the operating rod handle being swung to operate the coupler and Fig. 9 shows the operating handle returning to substantially vertical position with the inclined surface 23 engaging the member 9 and 35 about to raise the operating handle.

In both modifications it will be understood that when the coupler head moves longitudinally and/or laterally of the car the angular relationship of the rod and bracket 13 changes, and that consequently the bracket is constructed so as to compensate for said possible change of angularity of the rod so as not to interfere with the proper relationship and functioning of the inclined surfaces 11 and 14 and 22 and 23 with member 9.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A car coupler operating mechanism comprising a member fixed to the car, a guiding bracket fixed to the car, an operating rod mounted in said guiding bracket for rotating and vertical movement therein, said rod attached to said coupler for operation thereof upon rotation of said rod, a portion of said rod outwardly of said bracket being bent laterally in an ogee curve and downwardly to provide a depending handle, the portion of said curve adjacent said handle providing a hook portion engageable with said member to substantially prevent accidental rotation of said rod, said hook portion including an inclined surface arranged so that movement of said handle by an operator to operate the coupler raises said rod and disengages said hook portion from said member, whereby the weight of the rod tends to prevent accidental rotation of said rod.

2. A car coupler operating mechanism comprising a member fixed to the car, a guiding bracket fixed to the car, an operating rod mounted in said guiding bracket for rotating and vertical movement therein, said rod attached to said coupler for operation thereof upon rotation of said rod and provided with a depending handle, said handle provided with a hook portion engageable with said member to substantially prevent accidental rotation of said rod, said hook portion including an inclined surface arranged so that movement of said handle by an operator to operate the coupler raises said rod and disengages said hook portion from said member, said hook portion provided with another inclined surface adapted to engage said member upon return of said handle to substantially vertical position so as to raise said rod and guide said hook portion into engagement with said member, whereby the weight of the rod tends to prevent accidental rotation of said rod.

3. An operating rod for operating a car coupler upon rotation of said rod, said rod comprising a portion at one end adapted to be operatively connected to said coupler, a portion adjacent the opposite end for rotatable support within a bracket, said rod being bent laterally and downwardly to provide a handle portion for rotating said rod, said lateral portion providing a hook portion adapted to engage a member fixed to a car to substantially prevent accidental rotation of said rod, said hook portion provided with an inclined surface adapted to engage said member and raise said hook portion from engagement with said member upon movement of said handle to operate the coupler.

4. A structure as set forth in claim 3 wherein said handle is provided with another inclined sur-

face adapted to engage said member upon return of said handle to substantially vertical position so as to raise said rod and guide said hook portion into engagement with said member.

5. A structure as defined in claim 1 wherein said member supports the weight of said rod when said hook portion is engaged with said member and said bracket supports the weight of said rod during swinging movement of the handle to operate the coupler.

6. An operating rod for operating the lock lifter of a car coupler upon rotation of said rod, said rod comprising a handle portion adjacent one end thereof for rotating said rod on its axis of rotation, a portion at the other end of said rod adapted to operate said lock lifter upon rotation of said rod, said rod having a laterally disposed portion in substantially ogee form and adapted to engage and rest upon a car part extendable in the path of rotation of said laterally disposed portion to substantially prevent accidental rotation of said rod due to service movements of a car when said laterally disposed portion is resting upon said car part.

7. An operating rod for operating the lock lifter of a car coupler upon rotation of said rod, said rod comprising a journal portion adapted to be rotatably supported in a bearing attached to a car, a handle portion adjacent one end thereof for rotating said rod on its axis of rotation, a portion at the other end of said rod adapted to operate said lock lifter upon rotation of said rod, said rod being bent to provide a laterally disposed portion having a substantially ogee shaped under surface adapted to engage and rest upon a car part extendable in the path of rotation of said laterally disposed portion to substantially prevent accidental rotation of said rod due to service movements of a car when said laterally disposed portion is resting upon said car part.

8. An operating rod for operating the lock lifter of a car coupler upon rotation of said rod, said rod being bent to provide a laterally disposed portion having a substantially ogee shaped under surface adapted to hook over and rest upon a car part extendable in the path of rotation of said laterally disposed portion to substantially prevent accidental rotation of said rod due to service movements of a car when said laterally disposed portion is resting upon said car part.

9. An operating rod for operating the lock lifter of a car coupler upon rotation of said rod, said rod being bent to provide a handle portion for rotating said rod on its axis of rotation, said handle portion provided with a laterally disposed portion having an under surface formed with intersecting inclined planes adapted to hook over and rest upon a car part extending in the path of rotation of said laterally disposed portion to substantially prevent accidental rotation of said rod due to service movements of said car when said laterally disposed portion is resting upon said car part.
